UNITED STATES PATENT OFFICE

2,651,881

TOY KANGAROO

Marvin I. Glass, John W. Ehemann, and
Max R. Kraus, Chicago, Ill.

Application August 14, 1950, Serial No. 179,146

3 Claims. (Cl. 46—123)

1

Our invention relates to animated toys and more particularly to toys which may be actuated to project one or more objects from the body thereof.

One of the objects of our invention is the provision of a toy which may be in the representation of a kangaroo and which is adapted to contain within the body thereof one or more objects simulating baby kangaroos which may be caused to be projected from the pouch of the body upon actuation of the toy.

Another object of our invention is the provision of a toy of the foregoing character which is adapted to receive and to contain a plurality of objects which may be projected in sequence from the body of the toy and which objects may again be redeposited within the body for further projection therefrom.

A further object of our invention is the provision of a toy of the foregoing character which is simple in construction, durable in service and which provides a high degree of entertainment and amusement value.

Other and further objects and advantages of our invention will become apparent from the following description when considered in connection with the accompanying drawings in which:

Fig. 1 is a side elevational view of a preferred embodiment of our invention and showing the same in one position of operation.

Fig. 2 is a similar view showing our invention in another position of operation with an object being projected from the body thereof.

Fig. 3 is a top plan view of the device shown in Fig. 2.

Fig. 4 is a top plan view of an object intended to be projected from the body of the device.

Fig. 5 is a cross-sectional view taken substantially of line 5—5 of Fig. 4.

Figs. 6 and 7 are perspective views of the complementary body sections in separated relation.

Fig. 8 is an elevational view of the operating means in one position of operation.

Fig. 9 is a similar view showing the operating means in another position of operation.

Fig. 10 is a perspective view on an enlarged scale showing the operating means of my device in normal out of use position; and

Fig. 11 is a cross-sectional view taken substantially on line 11—11 of Fig. 3.

Referring to the drawings, our invention is illustrated as being embodied in the representation of a kangaroo, although it is to be understood that the operating means and principles of our invention may be embodied in other repre-

2

sentations of animals or figures. The embodiment illustrated comprises a pair of complementary body sections 16 and 17 adapted to be secured together to form a completed body 18. 5 As will be seen by reference to Figs. 6 and 7, the body section 16 is provided with a plurality of spaced cylindrical projections 19 which are adapted to register with and to be received in complementary openings 20 provided in the body section 17 thereby to effect alignment and securement of the sections into a unitary structure. Considering the body sections in assembled relation as a unitary structure, a chute 21 is formed in the upper portion of the body 18, the said chute being open at the top and bottom to accommodate a plurality of objects or projectiles 22 which may be in the representation of baby kangaroos. Ribs 23 projecting inwardly from the wall of the chute 21 serve to confine the projectiles in a desired path of travel. The body 18 also is provided with another chute 24 which is positioned so as to correspond to the pouch of a kangaroo, the chute being open at both ends and being inclined substantially as illustrated in Fig. 7.

The body supporting and operating structure indicated generally by the numeral 25 is illustrated more clearly in Figs. 8, 9 and 10 and includes a pair of leg members 26 at the upper end of which is disposed a basket-like member 27 which is inclined upwardly relative to the leg members and, as will be hereinafter described, is adapted to register with chute 21 or 24. The member 27 is open both at the top and bottom, 35 with the bottom opening being restricted so that objects or projectiles contained therein will not fall through the bottom opening. The leg members 26 are formed with rearwardly directed lugs 28 and 29, each having a stub shaft 31 which is adapted to register in a corresponding opening provided on the inner face of the body section 16 and 17, the stub shafts being coaxially disposed. Thus, the leg members 26 and associated structure are pivotally supported and are rockable 40 about the axis of the said stub shafts. Extending inwardly from each of the leg members 26 is an arcuately formed portion 34. These together form a closure member for the opening 36 provided in the bottom of the body 18. The basket member 27 is also provided with an arcuate rearwardly directed element 37 which functions to retain articles in the chute as will be hereinafter described.

50 The lug 29 is formed with a shoulder 32 which

acts in the manner of a cam as will be herein-after explained.

A trigger member, indicated generally by numeral 38, is shaped substantially as shown in the drawings and includes a longitudinal arm 39 and a transverse portion 41, the latter having a stub shaft 42 at each end thereof, the said stub shafts being received in coaxially aligned bearing portions 42a formed in the side walls of sections 16 and 17. The member 38 is formed with an integral wing portion 43 having a cam surface 43a which is adapted to coact with the shoulder 32, as will be herein-after described. The lower end of the longitudinal arm 39 is provided with a lateral extension 44 on which is anchored a coil spring 46, the opposite end of the said spring being attached to a projecting stub 47 integrally formed with one of the legs 26. Projecting forwardly from the longitudinal arm 39 and downwardly directed relative thereto is a hammer arm 48, the said arm having at its end a hammer 49 and an extension 50. The said hammer is of such size that it will enter into the lower opening of the basket member 27 when swung into registration therewith as will be herein-after explained.

A latch member indicated generally by the numeral 51 is formed with laterally directed stub shafts 52 which are received in suitable bearings 52a provided in the side walls of sections 16 and 17, the latch member being pivotable about the axis of the stub shafts 52. The forward end of the latch member 51 is provided with a cam portion 53 and a shoulder 54 while the opposite end of the said member is formed with an abutment 56. A hollow boss 57 is formed in the bottom of the body 18 and serves as a seat for spring 58 which is adapted to bear against the latch member 51 and to urge the same in a clockwise direction as viewed in Figs. 8 and 9.

The shoulder 54 of the latch member 51 is adapted to engage with the extension 50 to retain the trigger member 38 in retracted position during an interval of operation of the device. The cam surface 53 is adapted to engage with an inwardly directed projection 59 formed on one of the leg members 26 to effect disengagement of the shoulder 54 from the extension 50 in a manner as will be herein-after described.

The objects or projectiles 22 which are adapted to be received in the chute 21 may be of any suitable configuration and are here illustrated as being in the representation of baby kangaroos and are preferably weighted at the bottom through the use of a metal insert 22a so that they will always tend to assume an upright position.

In normal standing position, the body 18 assumes the position illustrated in Figs. 2, 6 and 7, with the foot portions of the leg members 26 resting flat on a supporting surface. The relative positions of the operating parts are illustrated more clearly in Fig. 10. The basket member 27 is directed forwardly with the mouth thereof out of registration with the lower opening of the chute 21 but in registration with the chute 24 and the portion 37 covering the lower opening of chute 21 to retain any objects such as projectiles 22 which may be in the chute. In order to effect actuation of the device, assuming that one or more projectiles have been placed within the chute a downward pressure is applied to the body, thus causing the leg members 26 to rock in a clockwise direction, as viewed

in Fig. 1, about the axis of the shafts 31 to assume the position illustrated in Figs. 1 and 8. In this position the basket member 27 is aligned with the lower opening of the chute 21 so that one of the objects or projectiles 22 contained within the chute may fall into the basket member 27. Also the projection 59 is out of engagement with the cam surface 53 on the latch member 51. Correspondingly, the cam portion 32 which is in engagement with the wing portion 43 acts to swing the trigger member 38 to the position illustrated in Fig. 8 so as to move the hammer head 49 at the end of arm 48 away from the lower opening in the basket member 27. Additionally, the latch member 51 is urged by spring 58 in a clockwise direction about the axis of the stub shafts 52 so that the shoulder 54 engages with the extension 50 at the end of arm 48 thereby retaining the trigger member 38 in cocked position, as illustrated in Fig. 8. Pivotal movement of the latch member 51 in a clockwise direction is limited by engagement by the abutment 56 with the inside surface of the tail portion of the body 18. Upon removal of downward pressure on the body 18, the spring 46 acts to return the leg members 26 and the trigger member 38 to the normal position illustrated in Fig. 10. As the leg members 26 move towards normal position, the cam surface 53 at the end 30 of the latch member 51 is caused to engage with the projection 59 attached to one of the leg members 26 effecting a counterclockwise rocking of the latch member 51. At a point coinciding substantially with normal position of the leg members the shoulder 54 becomes disengaged from the wing portion 50 thus releasing the trigger member which swings in a clockwise direction as viewed in Fig. 9 to cause the hammer 49 to enter the opening at the bottom of member 27 and impinge on the projectile 22 disposed therein with sufficient impact to project the projectile through the chute 24 and into the air for a short distance. The projectile being provided with a weighted base upon landing on a surface will assume an upright position. When the trigger member 38 returns to normal position the projection 37 acts as a stop to prevent other projectiles from falling through the chute.

It will be apparent that upon successive applications and release of pressure on the body 18 in the manner hereinabove described, all of the projectiles contained within the chute 21 may be successively projected through the air. Thus an effect is obtained of a number of baby kangaroos jumping from their mother's pouch. After the discharge of all of the projectiles from the body of the device, the body may be reloaded by inserting the projectiles into the chute through the opening in the head portion of the body.

60 We claim:

1. A toy device comprising a body in the representation of a kangaroo, said body having an open ended chamber and an opening corresponding to the pouch of a kangaroo through each of which a projectile may be passed, said body supported on leg members pivotally attached thereto, a receptacle for said projectile carried on said leg members and adapted to register alternately with said chamber and said opening, a hammer member pivoted in said body and having a hammer head arranged to register with an opening in the bottom of said receptacle so as to impinge on a projectile contained therein, said hammer being operatively associated with said legs so that when said leg members are rocked in one di-

rection a projectile will be deposited within said receptacle and said leg members upon being rocked in the opposite direction causing said hammer head to impinge on said projectile to project the same through said opening.

2. A toy device comprising a body in the representation of a kangaroo and adapted to contain a plurality of projectiles, said body supported on leg members pivotally attached thereto and having an opening corresponding to the pouch of a kangaroo through which projectiles may be passed, a receptacle for one of said projectiles carried on said leg members and adapted to register with said opening, a hammer member pivoted in said body and operatively associated with said leg members, said hammer member having a hammer head arranged to register with an opening in the bottom of said receptacle so as to impinge on a projectile contained therein, said leg members when rocked in one direction positioning said receptacle to receive a projectile and retracting said hammer head, said leg members when rocked in an opposite direction positioning said receptacle in registration with said opening and releasing said hammer head to impinge on said projectile to project the same through said opening.

3. A toy device comprising a body in the representation of a kangaroo, said body having a chamber open at each end and adapted to receive a plurality of projectiles and having an opening corresponding to the pouch of a kangaroo through which a projectile may be passed, leg members supporting said body and pivotally attached thereto, said leg members carrying a receptacle for containing one of said projectiles and having a cam associated therewith, a hammer

member pivoted in said body and operatively engageable by said cam so as to be rocked simultaneously with said legs, said hammer member having a hammer head arranged to register with an opening in the bottom of said receptacle so as to impinge on a projectile contained therein, spring means normally urging said hammer head in a direction towards said receptacle, a latch member engageable with said hammer member to retain the same in retracted position, said leg members when downward pressure is applied on said body being rocked in one direction to position said receptacle in registration with said chamber to receive a projectile and to rock said hammer head to retracted position and in engagement with said latch member, said leg members when pressure on said body is removed being rocked in an opposite direction to position said receptacle in registration with said opening, and means engageable with said latch member to release said hammer head to cause said hammer head to impinge on said projectile to project the same through said opening.
